Martin Jachimow

UNITED STATES PATENT OFFICE

HARRY HERTZBERG, OF BROOKLYN, NEW YORK

OIL MOP

Application filed February 20, 1928. Serial No. 255,823.

This invention relates to improvements in oil mops and more particularly to means for securing the mop to its mop stick and to means for expanding the mop frame. It is 5 an object of this invention to provide a mop of very simple and inexpensive construction but yet rigid and durable to perform efficiently all the functions required from a mop of this kind.

10 With this and other objects in view which will become clearer as the description progresses the invention consists in a novel construction and combination of parts herein-after fully described and finally pointed out 15 in the appended claims.

In the drawings which form a material part of this disclosure:

Fig. 1 is a plan view of a mop embodying the invention.

20 Fig. 2 is a side elevation of the same mop partly in section on line 2—2 of Fig. 1.

Fig. 3 is a detail section of the frame expanding means on line 3—3 of Fig. 1.

Referring to the drawings 10 is a metallic 25 frame having the shape of an equilateral triangle provided with rounded corners. This frame is preferably made from a flat metallic bar bent into the shape of a V the legs of which form an angle of about 150 degrees as 30 shown in section in Fig. 2, the groove formed in this manner is directed towards the outside of the frame. One side of this triangular frame is non-continuous as the end portions of the metallic bar are bent at corners 10^a 35 towards the center part of the triangle forming two substantially parallel flat plates 11 separated from each other to form a space for mop stick 15. The V groove in the frame ends at points 10^a and plates 11 are bent 40 in their middle portion at 11^b so that the space between them is slightly larger near 10^a than in the forward part. The free ends 11^a of the plates hold the mop-stick 15 by means of a pivot bolt 12 which passes through 45 apertures in plates 11 and also in mop stick 15. Bolt 12 is adapted to draw the plates 11 together and to tighten the mop stick between them in any desired angular position.

The rearward portions of plates 11 between 50 points 10^a and 11^b are also provided with

apertures opposite each other through which a bolt 16 passes. A nut 17 on bolt 16 presses the plates 11 towards each other. This bolt 16 carries in the space between plates 11 tubular expansion members 18 and 19 of which 55 18 is provided with an external, and 19 with an internal thread, forming means to increase or decrease the length of the expansion member and to spread plates 11 apart.

The mop material comprises a plurality of fabric strands 20 which are looped over at their middle portion and secured within outer and inner fabric covering bands 21 and 21^a. They are sewed together on lines 22 and 23 thus affording a tubular space through 60 which a steel wire 14 passes. The tubular portion formed by the fabric bands 21 and 21^a lies in the V groove of frame 10 and surrounds the triangle which is formed by this frame. The ends of wire 14 are joined within 65 the opening of the frame 10 between the two points 10^a by twisting them together and thereby holding the mop material tight on the frame 10. When the mop material is in place on the frame it is desirable to stretch the fabric bands holding the mop material and also wire 14 so that the material becomes tied closely to frame 10 in its groove. This 70 also becomes necessary when the mop material has become loose by stretching after being in use for some time. For this purpose I have provided the expansion member 75 18—19 which spreads the points 10^a apart and with them elongates the open side of the triangle increasing its periphery and tightening the mop material onto frame 10. In addition to this spreading action the expansion member adds to the rigidity of the frame 80 10. The frame may also be contracted by means of the elements 16—17—18—19 so that the mop fabric tube 21 and wire 14 become loose thereon and can be removed without opening the wire joint at the center of the open space between the corners 10^a. It will 85 be noticed that the whole mop head consists of a single piece of metal, two bolts and the expansion member or spreader 18—19 and that a plurality of elements usually found in similar devices are eliminated by this invention.

Having thus described my invention what I claim as new and desire to secure by Letters Patent is:

1. In a mop of the kind described, an open frame having the shape of a loop, a break in said frame, a pair of parallel plates integral with said frame extending towards the center of the loop at either end of the break in said frame, mop material surrounding said frame, means to hold a mop-stick between the free ends of said plates and other means for increasing the distance between said plates gradually, to expand said frame against said mop material.
- 15 2. In a mop of the kind described, an open frame of loop shape, said frame consisting of a continuous metallic bar having end portions forming parallel plates projecting towards the center of the frame, a bolt to hold and to clamp a mop stick between the projecting ends of said bar and a compression member parallel to said bolt adapted to vary the distance between said projecting ends and to expand or contract said frame.
- 25 3. A mop frame comprising a metallic bar bent into the shape of a loop and having integral end portions arranged substantially parallel to each other at the rear of the loop which end portions project into the frame, a pair of bolts extending transversely through said parallel portions, one of said bolts holding a mop stick and the other bolt holding a tubular member adapted to vary the distance between said parallel portions and to expand said loop.
- 30 4. A mop frame consisting of a metallic bar bent into the shape of a polygon, an opening in one side, the end portions of said bar being bent inwardly at said opening parallel to each other, and means carried by said end portion to expand and contract said mop frame, said means consisting of a tubular member having a threaded joint for varying its length and a supporting bolt passing through said end portions and said tubular member.

In testimony whereof, I have signed my name to this specification this 15th day of February, 1928.

50 HARRY HERTZBERG.
